UNITED STATES PATENT OFFICE.

FRANCIS B. FARNSWORTH, OF GRANBY, QUEBEC, CANADA.

GATE FOR RAILWAY CROSSINGS.

Application filed June 16, 1925, Serial No. 37,508, and in Canada February 19, 1925.

My invention relates to gates for railway crossings of the type which are automatically operated by the travel of a train within a given zone in the proximity of the crossing.

The invention has for its object primarily, to provide a new and improved crossing gate and means for electrically lowering and raising the same which will be of comparatively simplified and inexpensive construction, and in which the danger of the gate failing to function at a critical time and of vehicles being damaged by the lowering of the gate will be practically eliminated.

To this end my invention consists of the construction, combination and particular arrangement of the parts hereinafter described and illustrated and pointed out in the claims.

For full comprehension, however, of my invention, reference must be had to the accompanying drawings, in which similar reference characters indicate the same parts, and wherein:

Figure 1 is a side elevation of a crossing gate constructed according to my invention;

Figure 2 is a plan view thereof;

Figure 3 is a diagrammatic view of the electrical operating means;

Figures 4 and 5 are sectional views taken on lines 4 and 5 respectively on Figure 1; and

Figure 6 is a plan view of the means for yieldingly maintaining the gate in its position at right angles to the highway.

Referring to the accompanying drawings the gate proper is indicated at 2, the railway tracks at 3, a railway vehicle in dotted lines thereon at 4 and the motor for lowering and raising the gate at 5.

In carrying out my invention in actual practice a pair of aligned gates each extending half way across the highway will be located on both sides of the crossing and will operate in unison with each other but for purposes of brevity I have herein described only one gate with its operating means.

The gate 2 consists of a balanced arm pivoted adjacent one end and adapted to be swung on its pivot vertically to and from position obstructing the highway in the proximity of the railroad crossing. It is also capable of being swung laterally when in its lowered position so that if the gates are lowered at a time when a vehicle is in the act of crossing the railway tracks the vehicle will be permitted to continue on its

way pushing the gate to one side when it encounters the latter. The danger of vehicles being trapped between the gates is thus avoided.

The preferred embodiment of my improved gate consists of a fixed post 6, a balanced arm comprising two normally longitudinally aligned sections 7 and 8, the section 7 being forked and hinged as at 9 upon the post in position straddling the same and having counterweighted ends 10, and the other section 8 being pivotally mounted upon one end of the first mentioned section in a manner to be presently described. These two sections are normally maintained in their relative longitudinal alignment by a pair of tensional springs 12 one end of each of which is connected to the adjacent counter-weighted arm of the section 7 and the other end of each to the underside of section 8 adjacent its pivot point through a chain 13. The latter extends over an anti-friction sheave 14 flanked by two additional sheaves 15 and 16 which are engaged by the chain only when the section 8 is swung laterally on its pivot. All three sheaves are mounted upon the underside of the section 7.

As it is desirable to prevent the section 8 from swinging laterally relatively to the section 7 when the gate is in its raised position means is provided for automatically locking the two sections together when the gate is raised and for automatically releasing the same when the gate is lowered.

This means consists of two normally aligned locking members 17 and 18 and a locking slide 19 adapted to simultaneously engage both members when the gate is raised and hold them against relative movement. The member 17 is fixed upon the top of the gate section 7 and slidably carries the slide and the other member 18 is pivoted on the section as at 21 on a vertical axis in alignment with the fixed member and hinged as at 21a the other gate section 8 and forms a part thereof. The relative dimensions of the locking members, slide 19 and link 20 are such that when the gate is lowered the slide will be withdrawn by link 20 from member 18 so that the latter with gate section 8 may be swung laterally on its pivot. The slide 20 is preferably of inverted channel cross-section with its sides turned in as at 22 and embracing outwardly extending flanges 23 on the members.

The motor 5 for operating the gate is

rotatably connected to the shaft 9 on which the gate swings through a train of gears comprising a worm 30 on the motor shaft 31, a worm wheel 32 keyed on a shaft 33 and 5 intermeshing with the worm, a pinion 34 also keyed on the shaft 33 and rotatable with the worm wheel and a comparatively large segmental gear 35 keyed on the shaft 9 and intermeshing with the pinion.

10 In the event of a train coming within a given distance of the crossing constituting a safety zone the motor automatically lowers the gate and the latter will remain in this position until the train has moved out of the 15 safety zone, in which event the motor will automatically return the gate to its normal position.

The means for effecting this automatic functioning of the motor comprises a source 20 of power 36, a normally open track circuit 37 connected to the lower source and adapted to be closed by a train coming within the safety zone of the crossing, and two normally open motor circuits 38 and 39 respectively, each of which is adapted when closed to drive the armature of the motor in the opposite direction in which it is driven by the motor.

30 The track circuit comprises the source of power 36 the electromagnetic coil 40 of a relay 41 and both rails 42 and 43 of a certain section of the railway track within the safety zone of the crossing, all connected in series with the exception that there is no 35 connection between the rails, the gap therebetween remaining normally open until the circuit is closed by the wheels of a railway vehicle moving over the section of track included in the circuit.

40 When the track circuit is closed the electromagnetic coil of the relay, being energized, attracts its armature 44 consisting of a resilient member carrying two oppositely disposed contacts 45 and 46 respectively, to position in which contact 45 will engage a fixed contact 47 and close the motor circuit 38.

45 This circuit which includes the windings of the motor is connected to the power source so that when it is closed the armature of the motor is rotated in the direction indicated by the arrows in full lines in Figure 1, causing the gate to swing down in juxtaposition with the track, and obstructing the highway. In order to automatically open this 50 circuit when the gate has been swung down to the desired position a pair of contacts 48 and 49 forming a part of a duplex rotary switch 50 common to both motor circuits, is included in the circuit 38. One of these contacts 48 resiliently bears against the other contact 49. The latter contact is rotatable with shaft 9 and is of such a length and so positioned relatively to the turning movement of the latter that it moves out of en-

gagement with contact 49 at the end of the downward movement of the gate, and thereby opens the circuit.

Notwithstanding the fact that the motor circuit is thus opened the gate will remain 70 in its lowered position until the track circuit is opened. The opening of the track circuit may be effected by the passage of the train from the safety zone or by an emergency switch to be presently described, in which 75 event the electromagnetic coil 40 of the relay 41 will be demagnetized and allow the resilient armature 44 to return to its normal position. In this position its contact 46 engages a fixed contact 51 and closes the 80 motor circuit 39. This circuit is similar to motor circuit 38 with the exception that the polarity of its terminals is reversed so that the flow of current through the motor windings takes place in the opposite direction, and consequently the armature of the motor is rotated in the opposite direction to that in which it is rotated when the motor circuit 38 is closed. The train of gears actuating the gate is consequently also rotated in the reverse direction and the arm is swung upwardly to its initial position at which point the circuit is broken by a pair of contacts 52 and 53 forming a part of the duplex switch 50 and rotatable with shaft 9.

95 In order to permit of the lowering and raising of the gate independently of the travel of railway vehicles in the safety zone two switches 70 and 71, which may be manually operated from any convenient point, are included in the track circuit. The former is normally closed and need only be opened when it is desired to open the gate while a railway vehicle is within the safety zone in position closing the track circuit. For instance if a locomotive is shunting within the safety zone the gate may be opened at intervals to allow the passage of the highway traffic without necessitating the withdrawal of the locomotive from the 100 safety zone. The other switch 71 which is included in a shunt 72 around the track rails is kept normally open and need only be closed in an emergency in the event of the approach of a train failing to effect the 105 automatic operation of the gate or when it is desirable to lower the gate independently of the track rails for any reason.

110 What I claim is as follows:

1. In a protective means for railway crossings a gate pivoted at one end and adapted to be lowered and raised to and from position obstructing a highway, said gate being constructed and arranged to be 115 swung horizontally, and means for automatically locking the gate against said horizontal movement when in its raised position and for releasing it when in its lowered position; an electric motor for lowering and raising the gate; a normally open track cir- 120 125 130

- cuit adapted to be closed when a railway vehicle comes within a given distance of the crossing; a pair of normally open independent motor circuits including the motor and 5 a source of power, each of the circuits being adapted to drive the motor in the opposite direction to the other; electromagnetic means constructed and arranged to close one of the motor circuits when the track circuit 10 is open, and a duplex rotary switch controlled by the movement of the gate, said switch being constructed and arranged to automatically open, when the gate has been raised or lowered a predetermined extent, 15 the motor circuit causing the said last mentioned movement of the gate, substantially as described.
2. In a protective means for railway crossings a gate pivoted at one end and 20 adapted to be lowered and raised to and from position obstructing a highway, said gate being constructed and arranged to be swung horizontally, and means for automatically locking the gate against said horizontal 25 movement when in its raised position and for releasing it when in its lowered position, a normally open track circuit adapted to be closed when a railway vehicle comes within a given distance of the crossing; a pair of 30 normally open independent motor circuits including the motor and a source of power, each of the circuits being adapted to drive the motor in the opposite direction to the other; electric magnetic means constructed 35 and arranged to close one of the motor circuits when the track circuit is closed, and to close the other circuit when the track circuit
- is open, and a duplex rotary switch controlled by the movement of the gate, said switch being constructed and arranged to 40 automatically open, when the gate has been raised or lowered a predetermined extent, the motor circuit causing the said last mentioned movement of the gate, substantially as described, and manually operated means 45 for controlling the circuit for the purpose of causing the operation of the gate independently of the circuit controlling properties of the railway vehicle, substantially as described. 50
3. In a protective means for railway crossings a gate pivoted at one end and adapted to be lowered and raised to and from position obstructing a highway, said gate being constructed and arranged to be 55 swung horizontally, and means for automatically locking the gate against said horizontal movement when in its raised position and for releasing it when in its lowered position, substantially as described. 60
4. In a protective means for railway crossings a gate consisting of a balanced arm comprising a part pivoted to swing vertically and a second part pivoted on the first part and adapted to swing vertically in unison therewith and laterally relatively thereto, and means for yieldingly maintaining the parts in longitudinal alignment, and means for automatically locking the second part against said lateral movement and for 65 releasing the same. 70

In testimony whereof I have signed my name to this specification.

FRANCIS B. FARNSWORTH.
